US00D744947S

(12) **United States Design Patent**
Rabalais et al.

(10) **Patent No.:** **US D744,947 S**
(45) **Date of Patent:** **** Dec. 8, 2015**

(54) **POWER SUPPLY FOR A BATTERY CHARGER**

(71) **Applicant:** **The Gillette Company**, Boston, MA (US)

(72) **Inventors:** **Brian Adam Rabalais**, New Milford, CT (US); **Eric Justin Price**, Wilton, CT (US); **Francisco Jose Restrepo**, Norwalk, CT (US); **Chen Jian**, ShenZhen (CN); **Zhang Yun**, ShenZhen (CN); **Paul Edward Backett**, Portland, OR (US); **David John Sayler**, Portland, OR (US); **Chunshik Kim**, Portland, OR (US)

(73) **Assignee:** **The Gillette Company**, Boston, MA (US)

(**) **Term:** **14 Years**

(21) **Appl. No.:** **29/526,158**

(22) **Filed:** **May 7, 2015**

(57) **CLAIM**

The ornamental design for a power supply for a battery charger, as shown and described above.

DESCRIPTION

FIG. 1 is a top perspective view of a design for a power supply for a battery charger of the present invention;

FIG. 2 is a top view thereof;

FIG. 3 is a bottom view thereof;

FIG. 4 is a front view thereof;

FIG. 5 is a back view thereof;

FIG. 6 is a right side view thereof;

FIG. 7 is a left side view thereof; and,

FIG. 8 is a bottom perspective view thereof.

The broken lines shown in the drawings are included for the purpose of illustrating environmental structure and form no part of the claimed design.

1 Claim, 7 Drawing Sheets
